UNITED STATES PATENT OFFICE.

CHARLES G. DUGANNE, OF WASHINGTON, DISTRICT OF COLUMBIA.

GOLF TEE.

Application filed March 28, 1928. Serial No. 265,411.

This invention relates to devices for use in playing the game of golf, and more particularly to golf tees adapted to support the golf ball in an elevated position, preparatory to the drive.

The object of the invention is the provision of a tee which is equipped with means insertible into the ground, whereby to hold the tee in upright position, and yet which may be so economically manufactured as to justify the discard thereof after several usages, in the event of slight damage from the strokes.

A further object of the invention is the provision of a tee which is equipped with a plurality of normally flat wings adapted to be quickly adjusted to operative or ball-holding position.

Other objects of the invention will be made apparent in the following specifications, when read in connection with the accompanying drawings forming a part thereof.

In said drawings:

Fig. 1 is a perspective view of a tee embodying my invention.

Fig. 2 is a front plan view of the tee in inoperative position.

Fig. 3 is a side view of the tee in operative position.

Fig. 4 is a side elevation of one of the wing forming members of the tee.

Fig. 5 is a plan view, partly in section, showing a modified form of supporting shaft, and,

Fig. 6 is a section on the line 6—6 of Fig. 4.

Now referring specifically to the drawing in which like reference numerals indicate like parts throughout the several views, 1 is a metallic supporting shaft, having a looped portion 2, and a pointed end 3, here illustrated in Figs. 1 to 3, as a wire doubled upon itself, and twisted at its free ends.

The looped portion 2 of the shaft 1 surrounds and closely embraces two wing members 4, 4, along the central vertical axes thereof, the extreme top portion of the wire forming the shaft lying in a notch 5 formed in each of the wing members 4, whereby to prevent the surface of the wire from extending beyond the top edges of said members.

The wing members 4, 4, may be constructed of any sufficiently rigid flexible material of

a strength adequate to operatively retain a golf ball on their edges. Thin card-board, 55 or relatively thick paper is adapted to this use, but I prefer to construct the wings 4 from two-ply paper having a malleable wire 6 enclosed by the paper layers, thereby insuring the necessary strength and providing 60 a wing structure such that the ball-supporting members will maintain any adjusted position. A wing 4 so formed is illustrated in section, in Fig. 6. Wings made of such prepared material are of especial advantage, 65 in that, after the tee has been used, the player may press the wings together, flatly in parallelism, and the more easily carry the tee in his pocket, if desired. Furthermore the wire 6 strengthens the wings and manifestly lengthens the life of the tee.

In manufacture, a loop of the wire forming the shaft 1, is laid in aligned notches 5, 5, in two wings placed in parallel contact, and the looped portion 2 of the wire is 75 grasped in a vice, or by pliers, and the lower free ends are twisted together until the internal surfaces of the wire forming the loop 2 is in contact with the top and bottom edges of the wings 4, the extreme top of the portion of the wire forming the loop being 80 nested in the notches 5, 5, as will be understood.

In Fig. 5 I have illustrated a modified form of the supporting shaft 1. In this embodiment of the invention I may utilize a shaft of slightly bendable metal, such as provided for the ends commonly used on shoe laces. The material should be pointed however, and of sufficient rigidity to be pushed 90 into the ground, and the upper end is vertically split to receive the wings 4, 4. After the wings are inserted, the extreme top portion of the shaft may be crimped with a suitable tool, as will be understood.

From the foregoing it will be obvious that I have provided a golf tee which is very economical from a manufacturing standpoint, and which is efficient in operation, and adapted for foldable adjustment into 100 compact inoperative position. The wings 4 are about an inch long and substantially one-half inch wide at the narrowest portion, tapering downwardly and inwardly along their top edges, to provide a concaved seat 105 for the golf ball. An attractive feature in

cident to the use of such tees is that advertising matter may be printed on the sides of the wings, with all the attendant advantages, incident to the manufacturer or vendor of the tees.

Various modifications of the structure herein disclosed may be suggested to those skilled in the art, but my invention covers all embodiments falling fairly within the scope of the appended claims.

I claim:—

1. A golf tee comprising a plurality of wing members each provided with a centrally positioned notch in its upper edge, and a wire carrying a loop surrounding said members and having its upper portion seated in said notches, the lower ends of said wire being twisted to form a supporting shaft.
2. A wing for golf tees, comprising a flexible member having an inwardly and downwardly tapering upper edge, a notch provided in the lowest portion of said edge, and a wire of pliable material extending longitudinally of said wing.
3. A golf tee comprising a plurality of wing members having an upper edge shaped to receive a ball, and a tee supporting shaft enclosing the central portion of said members and clamping them together.

4. A golf tee comprising a plurality of flexible wing members each having an upper edge shaped to receive a ball, and a tee supporting shaft comprising a wire enclosing the central portion of said members, and twisted to facilitate the insertion thereof into the ground.

5. A golf tee comprising a ball supporting member, and a twisted wire embracing said member and adapted for insertion into the ground.

6. A golf tee comprising a ball supporting member, and a wire looped around the central portion of said member and depending therefrom, the lower portion of said wire being twisted to adapt it for insertion into the ground.

7. A golf tee comprising a ball supporting member concaved at its top to receive a ball, said member being provided with a downwardly extending notch at the point of lowest concavity, and a wire having a looped portion lying in said notch and embracing said member, said wire being twisted, below said member, to facilitate insertion into the ground.

In testimony whereof I affix my signature.

CHARLES G. DUGANNE.
